OUTLET BOX HOLDER

Audley P. Bell, Claysville, Pa.

Application June 18, 1951, Serial No. 232,159

1 Claim. (Cl. 248—27)

1

The invention relates to holders, for electrical outlet boxes known as switch boxes installed in the walls of buildings. Such outlet boxes are customarily provided with lateral ears or flanges abutting against the front side of the wall of a room within an opening of which wall the switch box fits, said lateral flanges limiting the projection of the switch box through the wall opening and being provided with perforations for screws or the like to secure the switch box in place. In construction work of buildings wherein the walls of the rooms have plaster board, beaver board, rock lath or gypsum wall board or the like substituted for the wood laths and plaster, the screws or nails will not have a secure hold and therefore it is necessary to provide other means to hold the switch box in place. An object of the invention is to provide a holder for a switch box located within an opening of the plaster board facing of the wall of a room with its lateral flanges contacting the front side of the plaster board, said holder being formed of spring sheet metal into a bow, the free end of one leg of the bow being adapted to contact the adjacent back side of the plaster board, the other leg of the bow having a reversely bent extension spaced from the outer side of said other leg to provide a hook of which said other leg forms part for the reception of the free end portion of the adjacent side wall of the switch box, the opposite inner side wall faces of said hook being adapted to bear against the inner and outer faces of the adjacent side wall of the switch box in such manner that pressure exerted upon the hook at the front side of the plaster board will be transmitted through the bow to said free end to cause the holder to pivot upon said free end and bring said hook into tight embracing engagement with the adjacent side wall of the switch box. A further object is to provide such a switch box holder wherein no tools of any kind are required to install the holders to secure the switch box in place; wherein there is no need for parts of the holders to be manually bent or adjusted in the application of the holders; wherein there is no possible chance of the holders being dropped within the space between the plaster board sides of the wall of a room; wherein the holders can be installed in ten seconds; wherein the holders may be removed equally expeditiously; wherein it is not necessary for any knockouts to be removed from the switch box prior to the application of the holders; wherein no special spring metal or steel is required for the holders, and wherein the holders are capable of being made in quantity at small cost so that they may be made in quantity at small cost so that they may

be sold at a small price. Other objects and advantages will appear hereinafter or will be obvious.

The invention consists in the novel construction and combinations of parts as hereinafter set forth in the claim.

In the accompany drawings,

Figures 1 and 2 are sections taken on the line 2—2, Figure 3, showing the switch box holders in first and final positions of installation.

Figure 3 is a front elevation, showing the switch box in place in the opening of the plaster board, and the switch box holders in final position of installation, one of the switch box holders being shown in full lines, the plaster board being broken away partly.

Figure 4 is a perspective view of one of the switch box holders.

In the drawings, 1 designates the switch box holder formed of spring sheet metal into a bow the span of which is at least equal to its height, said bow having a middle gradually curved portion 4 and oppositely inclined diverging legs 2 and 11, the toothed free end 5 of one leg 11 of the bow being adapted to contact the adjacent back side of the plaster board facing 6 of the wall of a room within an opening 7 of which the switch box fits with its lateral flanges 8 contacting the front side of the plaster board, the other leg 2 of the bow having a reversely bent extension 9 having an inclination similar to that of said other leg 2, said extension 9 being spaced from the outer side of said other leg 2 to provide a hook 1 of which said other leg forms part for the reception of the free end portion of the adjacent side wall of the switch box 3. The opposite inner side wall faces of said hook 1 are adapted to bear against the inner and outer faces of the adjacent side wall of the switch box 3 in such manner that pressure exerted upon the hook 1 at the front side of the plaster board will be transmitted through the bow 2, 4, 11 to said free end 5 to cause the holder to pivot upon said free end 5 and bring said hook 1 into tight embracing engagement with the adjacent side wall of the switch box.

In installation, two of the switch box holders are inserted preferably simultaneously upon opposite sides of the switch box, between the same and the edges of the opening 7 of the plaster board 6, the insertion being made by first entering the free ends 5 of the holders and thereafter pushing the holders within said opening to Fig. 1 position, wherein the free ends 5 contact the

adjacent back side of the plaster board and the opposite side wall faces of each hook 1 have initial bearing against the inner and outer faces of the adjacent side wall of the switch box, further movement of the holders from Fig. 1 towards Fig. 2 position being resisted by such bearing. The two holders are then forced home from Fig. 1 to Fig. 2 position, during which forcing the opposite inner and outer faces of each hook 1 bear against the inner and outer faces of the adjacent side wall of the switch box in such manner that pressure exerted upon the hook 1 at the front side of the plaster board will be transmitted through the bow 2, 4, 11 to said free end 5 to cause each holder to pivot upon its free end 5 and bring its hook 1 into tight embracing engagement with the adjacent side wall of the switch box 3. In the event the switch box fits tightly within the opening 7 of the plaster board with sufficient play to admit of the entrance of the holders to Fig. 1 position, the use of one of the holders will secure the switch box in place. In the event the switch box fits loosely within the opening 7 of the plaster board with more play, two of the holders are required to secure the switch box in place.

My switch box holders will accommodate themselves to plaster board of varying thicknesses, being self adjustable due to the spring metal of which they are made and the bowed form of the holders. The leg 11 of the bow is preferably plane or flat to adapt it to better resist the strain to which it is subjected.

The teeth of the free end 5 of the switch box holder are preferably bent slightly inwardly of the holder, in order that they may better resist skidding upon the back side of the plaster board under strain.

The right is reserved to modifications coming within the scope of the claim.

The reversely bent extension 9 may be provided

with a slot 10 wherein the end of a prying tool such as the blade of a screw driver may be inserted for the purpose of removing the holder from the switch box.

I claim:

A holder for an electrical outlet box located within an opening of the plaster board facing of the wall of a room with its lateral flanges contacting the front side of the plaster board, said holder being formed of spring sheet metal into a bow the span of which is at least equal to its height, said bow having a middle gradually curved portion and oppositely inclined diverging legs, the free end of one leg of the bow being adapted to contact the adjacent back side of the plaster board, the other leg of the bow being provided with a reversely bent extension having an inclination similar to that of said other leg, said extension being spaced from the outer side of said other leg to provide a hook of which said other leg forms part for the reception of the free end portion of the adjacent side wall of said box, the opposite inner side wall faces of said hook being adapted to bear against the inner and outer faces of the adjacent side wall of said box in such manner that pressure exerted upon the hook at the front side of the plaster board will be transmitted through the bow to said free end to cause the holder to pivot upon said free end and bring said hook into tight embracing engagement with the adjacent side wall of said box.
